[57] CLAIM

I claim the ornamental design for a ash tray, as shown and described.

DESCRIPTION

FIG. 1 is a front upper perspective view of a ash tray showing my design.

FIG. 2 is a side upper perspective view thereof, with the design rotated 120° from FIG. 1;

FIG. 3 is an opposite side upper perspective view thereof, with the design rotated 240° from FIG. 1;

FIG. 4 is a front view thereof;

FIG. 5 is a back view thereof;

FIG. 6 is a top plan view thereof; and,

FIG. 7 is a bottom plan view thereof.
